UNITED STATES PATENT OFFICE.

PETER THOMSEN, OF CASSEL, GERMANY, ASSIGNOR TO SCHMIDT'SCHE HEISSDAMPF
GESELLSCHAFT M. B. H., OF CASSEL-WILHELMSHOHE, GERMANY.

STEAM BOILER.

Application filed April 28, 1925, Serial No. 26,324, and in Germany May 2, 1924.

My present invention relates to steam boilers, and particularly such as are intended to produce high pressure steam for portable engines, for instance locomotives.

According to this invention, the boiler comprises four drums or steam and water containers extending longitudinally from the fire box to the smoke box, there being on each side of the boiler an upper and a lower container connected by water tubes. The side walls of the fire box are formed by water tubes extending from said containers to water boxes or chambers located below the level of the lower containers and preferably arranged laterally of the grate, at the same level therewith; the grate may be located between the drive wheels of the locomotive.

By providing two upper containers, I am enabled to make them of smaller diameter and therefore of thinner metal than when a single upper container or drum is employed. The manufacture of the boiler is thus made easier and less expensive.

It is important that a thorough water circulation be insured in the containers, the fire box walls, and the water tubes. For this purpose, I connect the containers with the water chambers of the fire box in such a manner that water will circulate through all of the containers and through the water chambers. For instance, the water chambers on each side of the fire box may be connected by pipes in which the water ascends, alternately with the upper containers located on the same side and on the other side respectively, while the only direct connection from each lower container to the fire box is by pipes leading to the respective water chamber on the same side, the water travelling downwardly in these latter pipes.

A satisfactory and preferred example of my present invention is illustrated by the accompanying drawings, in which Fig. 1 is a somewhat diagrammatic longitudinal vertical section of a locomotive boiler embodying my invention; Figs. 2 and 3 are vertical cross sections on lines 2-2 and 3-3 respectively of Fig. 1.

The boiler shown comprises four steam-and-water containers or drums a , a' , b , b' , extending longitudinally from the fire box to the smoke box. They are represented as horizontal, although this is not essential.

On each side of the locomotive there is a

lower container or drum a or a' and a corresponding upper boiler or drum b or b' respectively, the boilers or drums, a , b , on one side being connected by water tubes c , while the containers or drums a' , b' on the other side are connected by water tubes c' . The upper drums or containers b , b' are relatively close together, while the lower containers or drums a , a' are much farther apart, their spacing corresponding approximately to the gauge of the track on which the locomotive is to travel, as indicated in Fig. 3. The side walls of the fire box are formed by water tubes connected with the upper containers b , b' and with water chambers d located at each side of the grate at a level below the lower containers a , a' and preferably between the drive wheels e of the locomotive. The two water chambers shown at opposite sides of the locomotive may form part of a continuous water chamber of rectangular or other suitable shape. The pipes f and f' , which lead from the left-hand water chamber d in Fig. 3 to the upper containers b and b' respectively, are arranged in regular alternation, and in close contact with each other at their lower portions, so as to form an unbroken or continuous side wall on that side of the fire box. Similarly, on the other side of the fire box, a continuous wall is formed by the lower portions of the pipes g and g' arranged alternately with each other and leading from the right-hand water chamber d to the upper containers b and b' respectively. As shown in Fig. 3 (and this is the preferred arrangement) the pipes f' are in the same transverse planes with the pipes g' , and the pipes f will be in the same transverse planes with the corresponding pipes g . The lower ends of these pipes or tubes f , f' , g , g' , where they are connected to the water chambers d , are made of somewhat reduced diameter, as indicated in Fig. 3, so that the desired close contact may be obtained between adjacent tubes.

On the outer sides of the tubular fire box walls thus formed, I have arranged on each side of the locomotive a second set of tubes h and h' respectively which connect the water chambers d directly with the corresponding lower containers or drums a and a' respectively. Since the walls formed by the tubes f , f' , g , g' , shield the tubes h , h' , from the direct heat of the combustion gases, the outer tubes h , h' , will be relatively cooler.

and the water will flow therein downwardly, while in the tubes f, f', g, g' , the water will travel upwardly.

If the water chambers d of the fire box were connected only with the respective containers located on the same side of the locomotive, there would be two entirely separate paths for the circulation of the water, one on each side of the locomotive. By employing the arrangement described, according to which each of the water chambers (left and right) is connected with containers on both sides of the locomotive, I obtain a thorough circulation of water through all four containers and through the fire box.

For instance, starting from the upper left-hand container b , there is water circulation through the following path: upper left-hand container b , water tubes c , lower left-hand container a , down-take pipes h , left-hand water chamber d , uptake pipes f' ; upper right-hand container b' , water tubes c' , lower right-hand container a' , down-take pipes h' , right-hand water chamber d , uptake pipes g , upper left-hand container b . In addition thereto, there is, of course, also an individual water circulation on each side of the boiler, for instance, on the left-hand side such circulation takes place through the following path: upper container b , water tubes c , lower container a , down-take pipes h , water chamber d , uptake pipes f , and upper container b .

In the longitudinal boiler located in front of the fire box, I have provided casings i between the lower containers a, a' . These casings serve to gather the cinders deposited thereon and to cover or close the greater part of the free space remaining between these containers, so that the furnace gases may be properly guided. For this purpose, the casings i are bent upwardly to a suitable extent at their front and rear ends, as indicated in Figs. 1 and 2. Furthermore, these casings are so constructed and arranged that they may be removed from the boiler forwardly through the smoke box door.

Various modifications may be made without departing from the nature of my invention as defined in the appended claims.

I claim:

1. A boiler comprising a fire box, a smoke box, upper left-hand and right-hand and lower left-hand and right-hand steam and water containers extending longitudinally from said fire box to said smoke box, water tubes connecting the said left-hand containers, other water tubes connecting the said right-hand containers, said fire box having a grate located below the level of said lower containers, water chambers located at opposite sides of said grate, and water tubes connecting said water chambers with said containers and forming side walls for said fire box.

2. A locomotive boiler comprising a fire box having a grate located between the drive wheels, a smoke box, upper left-hand and right-hand steam and water containers located above the level of said grate and extending longitudinally from said fire box to said smoke box, water tubes connecting the said left-hand containers, other water tubes connecting the said right-hand containers, water chambers located at opposite sides of said grate, between the drive wheels, and water tubes connecting said water chambers with said containers and forming side walls for said fire box.

3. A boiler comprising a fire box, a smoke box, upper left-hand and right-hand and lower left-hand and right-hand steam and water containers extending longitudinally from said fire box to said smoke box, water tubes connecting the said left-hand containers, other water tubes connecting the said right-hand containers, said fire box having a grate located below the level of said lower containers, connected water chambers located at opposite sides of said grate, and water tubes extending upwardly from said water chambers and forming side walls for the fire box, some of the last mentioned water tubes extending from the water chambers to containers on the same side of the boiler while others of said water tubes extend from said water chambers to containers on the opposite side of the boiler, whereby water may circulate through a path including containers and water chambers on both sides of the boiler.

4. A boiler comprising a fire box, a smoke box, upper left-hand and right-hand and lower left-hand and right-hand steam and water containers, extending longitudinally from said fire box to said smoke box, water tubes connecting the said left-hand containers, other water tubes connecting the said right-hand containers, said fire box having at each side water chambers located below the level of the lower containers, uptake water tubes extending from each of said water chambers alternately to the upper container on the same side and to the upper container on the other side, and down-take water tubes extending from each of the lower containers to the water chamber on the same side.

5. A boiler comprising a fire box, upper left-hand and right-hand and lower left-hand and right-hand steam and water containers extending longitudinally from said fire box, water tubes connecting the said left-hand containers, other water tubes connecting the said right-hand containers, said fire box having a grate located below the level of said lower containers, water chambers located at opposite sides of said grate, and water tubes connecting said water cham-

bers with said containers and forming side walls for said fire box.

6. A boiler comprising a fire box, upper left-hand and right-hand and lower left-hand and right-hand steam and water containers extending longitudinally from said fire box, water tubes connecting the said left-hand containers, other water tubes connecting the said right-hand containers, said fire box having at each side water chambers located below the level of the lower containers, uptake water tubes extending from each of said water chambers alternately to the upper container on the same side and to the upper container on the other side, and downtake water tubes extending from each of the lower containers to the water chamber on the same side.

7. A locomotive boiler comprising a fire box having a grate located between the drive wheels, upper left-hand and right-hand and lower left-hand and right-hand steam and water containers extending longitudinally from said fire box and located above the level of said grate, water tubes connecting the said left-hand containers, other water tubes connecting the said right-hand containers, water chambers located at opposite sides of said grate, between the drive wheels, and water tubes connecting

said water chambers with said containers and forming side walls for said fire box.

8. A boiler comprising a fire box, a smoke box, upper left-hand and right-hand and lower left-hand and right-hand steam and water containers extending longitudinally from said fire box to said smoke box, water tubes connecting the said left-hand containers, other water tubes connecting the said right-hand containers, said fire box having a grate located below the level of said lower connected water chambers located at opposite sides of said grate, and water tubes extending upwardly from said water chambers and forming side walls for the fire box, some of said last mentioned water tubes extending upwardly from each of said water chambers to the lower container on the same side of the boiler, while others of said water tubes extend from each water chamber to the upper container on the same side of the boiler, and still others of said water tubes extend from each water chamber to the upper container on the other side of the boiler, whereby a path is afforded for the circulation of water through all of said containers and water chambers.

In testimony whereof I have hereunto set my hand.

PETER THOMSEN.
